(57) CLAIM

The ornamental design for an accessory post, as shown and described.

DESCRIPTION

FIG. 1 is a perspective view of an accessory post of the new design;

FIG. 2 is top plan view of the accessory post of FIG. 1; FIG. 3 is a left side elevational view of the accessory post of FIG. 1;

FIG. 4 is a front elevational view of the accessory post of FIG. 1;

FIG. 5 is a right side elevational view of the accessory post of FIG. 1;

FIG. 6 is a bottom plan view of the accessory post of FIG. 1; and,

FIG. 7 is a rear elevational view thereof.

The broken-line disclosure in the views is for illustrative purposes only, with the claimed design being limited to the full-line disclosure.
